DEVICE FOR MILLING AND SEPARATING
ORES

John H. Deguer, Los Angeles, Calif.

Application February 19, 1934, Serial No. 711,937

1. Claim. (Cl. 209—191)

My invention relates to mills adapted for comminuting, principally, precious metal bearing ores by crushing and braying means as a preliminary step to a recovery of their valuable constituents; also involving a specific adaptation of classifying amalgamating, floating or other well known reducing means or methods.

A principal object of my said invention is to provide a small, comparatively light and compact, easily transported, and inexpensive unit adapted for the usual limited scale of operations of the individual miner or prospector for effecting the above mentioned processes of ore treatment; and which may be efficiently utilized in the treatment of any kind and character of ore in pursuance of the general objects above mentioned.

It is also an important purpose of said invention to provide crushing and grinding means which may be easily varied in accordance with the tenacity of the material being treated by the increase or decrease of the weights of pestle-sleds or shoes, and also to utilize the centrifugal force created by a rotary travelling movement of said sleds not only for said grinding process but also for the classification of the ore sands by their specific gravity; and where free milling gold values are to be recovered to utilize such centrifugal force also to throw the ground material which is suspended in water within the tank containing said grinding mechanism up and over a sloping amalgamation zone all as hereinafter specifically described.

Other objects, such as simplicity and economy of construction, low initial cost, ease and economy of operation, efficiency of action, and adaptability to a wide range of kinds of material to be treated, will be obvious to those of skill in the art to which this invention appertains, upon an examination of the detailed description to follow.

In the drawing, Fig. 1 is a side elevation partly in section of the principal parts of my said invention;

Fig. 2 is a sectional view on line 2—2 of Fig. 1;

Fig. 3 is a sectional view on line 3—3 of Fig. 2; but in addition showing the rake partially broken away in elevation.

Referring with more particularity to the drawing, the numerals of which designate similar parts throughout the several views, 4 indicates a tank consisting of a lower part 5 and an upper part 6 of increased diameter, connected by flared portion forming an inwardly sloping annular ledge 7, covered, when free milling gold values

are to be recovered, with a silvered copper amalgamation plate, the purpose of which will be hereafter described.

A removable annular bottom plate 8 is secured to the floor of tank 4 by bolts 9, said bottom plate, preferably made in four sections, being composed of manganese steel or other abrasion-resisting material, is provided to form the bottom of an annular mortar 10, and at its center to provide a mercury well 11. An increase in thickness of the outer portion of said bottom plates 8 is utilized to permit the sloping of its upper surface toward the center of the circle formed by its circumference. The outer annular area between the middle of the radius and the periphery of said bottom plate 8 is provided with a series of diametric grooves 12 each of a width and depth relative to the size of the ore to be ground, the remaining area of said bottom plate 8 being smooth. The wall of lower portion 5 of said tank above bottom plate 8 is lined with detachable hardened steel plates 13, which may be similarly grooved, secured to the wall of said lower tank portion 4 by bolts 14.

15 indicates the intake pipe through which ore, having been first crushed to suitable size, is carried to the annular mortar 10 by a flow of water, as later more specifically described, for grinding. A pulley, adapted for rotation by a source of power (not shown) is illustrated at 16 attached to shaft 17 to the opposite end of which pinion 18 is secured which meshes with beveled gear 19 secured to vertical shaft 20 which is rotatably supported in a suitable framework 21 by a collar and thrust bearing assembly 22. Shaft 20 extends downwardly through the top of the tank portion 6 where it is further provided with a suitable bearing 23.

On the lower end of shaft 20, inside of tank 4, a rotor element 24 is mounted, consisting of an arm having near its ends series of holes 25—25, which overhang the track for attachment of the pestle-sleds or shoes 26—26 as hereinafter described, said pestle-sleds being oppositely disposed in annular mortar 10, by means of chains 27—27 so that as the arm is actuated by the rotation of the shaft to which it is connected the pestle-sleds or shoes are dragged by said chains 27 around the annular channel of mortar 10.

The sleds or shoes 26, each consisting of a base 28 and walls 29—29 are formed of some abrasion-resisting material, such as manganese steel, said sleds conforming to the curvature of the interior of the annular channel-mortar. The front bottom edges of each of said sleds 26 are

beveled as shown at 30 for the obvious purpose of permitting them to ride over the pieces of ore being ground.

5 Due to the fact that gold is found with a variety of associated elements having different qualities of hardness, means are provided to vary the pressure of the pestle-sleds or shoes 26 (in order to avoid excessive consumption of power in their motivation) consisting of a plurality of removable weights 31—34 which may be applied to sleds 26 when necessary, depending on the retentivity of the ore to be ground.

10 Posts 32—32 are adapted to secure the weights within the sleds or shoes 26 as illustrated in Fig. 3. The speed at which the rotor arm is operated, increasing or decreasing the centrifugal force of the sleds, also obviously affects the pressure of the grinding surfaces.

15 Drag rakes 33—33, are attached in any suitable manner to each of sleds 25, being designed to stir and loosen the ground material.

20 34 indicates a series of discharge openings through which the fluid is decanted.

25 The operation of the device is as follows: Ore, previously crushed to a suitable size, is flushed into the mill by approximately four times its volume of water. Actuating mechanism to drag the sleds around in the mortar channel then being set in operation the sleds are caused to slide over the ore crushing and grinding it against the ribbed floor thereof, and by reason of the outward swing on the supporting drains, grinding particles of the ore between the outer walls of said sled and the side plates 13. As the ore is 30 ground to a suitable fineness it is thrown into suspension and decanted through one of the variable discharge ports or openings 34.

35 Free gold values by reason of the slope of the bottom plate 8 of the annular mortar 10 gradually settles or is worked toward the mercury well 11 in the center of tank 5 within the annular mortar channel, where released gold forms an amalgam. The ribbed upper surface of bottom plate 8 assists in the grinding of coarse pieces 40 of ore, the tendency being for the finely ground particles of the gangue to be thrown into suspension while the "free gold" tends to gravitate toward the center. The rotary movement of the sled is communicated to the liquid contents of 45 the tank, and the centrifugal force resulting from said rotation throws the ground material in suspension up over the amalgamation zone 7 where the fine or floured gold values become attached or amalgamated with the mercury of the amalgamation plate, which may be used to cover zone 7.

50 55 The variable discharge ports enable the opera-

tor to decant at levels where the fineness of the grind will meet the requirements of either flotation or cyanidation.

5 While I do not limit myself to any particular dimensions, the following may be illustrative of a practical embodiment of my invention showing the extreme compactness which is an important object thereof.

10 The mill itself may consist essentially of a tank made of size $\frac{3}{8}$ -inch boiler plate of a diameter varying from $2\frac{1}{2}$ to 8 feet and of a depth of from 30 to 40 inches, depending upon the grinding capacity desired. The bottom of the boiler plate tank is welded in a distance of approximately four inches and supported by heavy 15 angle irons welded across the bottom. The bottom manganese plates of the annular mortar 10 may be $1\frac{1}{2}$ inches thick at the outer edge and slope to 1 inch at the center of the mill. These bottom plates may be grooved to a depth of $\frac{1}{2}$ 20 inch and a width of $\frac{1}{4}$ inch, such grooves being $\frac{1}{2}$ inch apart and running from the periphery to the center, about one-half the width of the plate.

25 The lower portion 5 of the tank may be lined to a height of 8 inches by the manganese side plates 13, which plates being detachable may be replaced from time to time as they become worn out, as is also true of the bottom liners 8. The flare of the lower tank at its connection with the upper tank by the zone 7 may be from 10 to 16 30 inches depending upon the capacity desired, its slope being at a rate from 1 to 4, and being covered by silvered copper amalgamation plates only where free milling gold values are to be recovered.

35 Comparatively little power is needed to operate a device of the general capacity above indicated. A 1500-R. P. M. motor of one horsepower per ton will be sufficient to actuate a 10 to 1 reducing worm gear, which in turn drives the pulley on the pinion shaft, the worm gear pulley is one-half the size of the pinion pulley causing further reduction, which brings about a relatively slow rotary motion of the sled.

40 What I claim and desire to secure by Letters Patent, is:—

45 In a device for milling and separating ore, a tank, an annular mortar with perpendicular cylindrical sides and an inwardly sloping bottom forming a channel extending around the bottom of said tank, radial grooves in the upper surface 50 of the bottom of said mortar, pestle-sleds, means to increase the weight of said sleds, drag rakes attached to said sleds, and means to impel said sleds around said channel and over pieces of ore fed to said mortar.

55 JOHN H. DEQUER.
